UNITED STATES PATENT OFFICE.

EDWARD W. HILL, OF CHICAGO, ILLINOIS, ASSIGNOR TO A. B. DICK COMPANY, OF CHICAGO, ILLINOIS, A CORPORATION OF ILLINOIS.

STENCILING MATERIAL.

1,393,444.

Specification of Letters Patent. Patented Oct. 11, 1921.

Application filed February 27, 1920. Serial No. 361,714.

To all whom it may concern:

Be it known that I, EDWARD W. HILL, a citizen of the United States, residing at Chicago, in the county of Cook and State of Illinois, have invented certain new and useful Improvements in Stenciling-Material, of which the following is a specification.

My invention relates to stenciling material, and particularly to a novel form of carrier-sheet and to the combination of such a sheet with a stencil-sheet positioned thereon, with or without an absorbent backing-sheet or fluid-receiving pad interposed between the carrier and stencil-sheets.

My invention is particularly intended for use in connection with stencil-sheets of a dry but hygroscopic character, which are generally moistened before use, such, for example, as those described in Patent No. 1,101,258, granted June 23, 1914. I have found that in such stencil sheets, when combined with other dry sheets such as an absorbent backing, a paper carrier-sheet or the like, there is a tendency to deteriorate, largely because of the passage of elements of the impregnating composition of the stencil-sheet into the adjacent sheet or sheets.

My invention overcomes this objection by providing a single, permanent carrier-sheet for use with successive stencil-sheets, which are quickly secured to the carrier-sheet when the stencil is to be made, and detached therefrom when the stencil is to be put in the duplicating machine. The stencil-sheets will be kept in massed condition, that is, in stacks of stencil-sheets one upon the other, without any paper or other backings in contact with the same, until the stencils are to be made. By this means they will largely be prevented from deterioration as by drying out. The stencils after being written may also be retained massed until wanted for printing, and therefore kept in a desirably soft and pliant condition. The unused stencil-sheets and the completed stencils may be kept massed in humidors, if desired, in perfect condition for long periods.

The carrier-sheet of my invention is formed of a non-absorbent material, celluloid being preferred because sheets of the same are non-absorbent of the fluid used to soften the stencil-sheet, and because it has the necessary flexibility. It also has other desirable qualities, including its hardness.

When a stencil is to be made, a stencil-sheet is secured on the carrier-sheet, a moistened sheet of absorbent material being interposed between the two, the stencil-sheet being then stencilized by pressure as, for instance, by means of a stylus or the type of a writing machine.

I have found that improved results of important character accrue from the use of a hard backing surface such as I propose to use. The stencils have finer lines than when a softer backing surface is used, because of which the characters are more distinct, sharper and more uniform, and the work generally has better finish and quality. Because of the finer lines, also, a lighter deposit of ink is made on the reproductions from the stencil, so that less time is required to dry the sheets, there is less halo about the letters, less offset, and less lack of uniformity because of the deeper penetration of certain typewriter characters than others. Other beneficial results obtained by the use of the invention will be referred to herein-after.

In the preferred embodiment of my invention the stencil-sheet is permanently secured at its upper end to a paper strip, such as the stub of a paper carrier-sheet, which is provided with keyhole slots. These may be slipped over a row of bent tongues which extend upwardly from the surface of the celluloid carrier-sheet. A guard or abutment strip is fastened on the carrier-sheet, or a continuation thereof as hereinafter described, above the projections, to be contacted by the upper edge of the stencil-sheet, to aid in properly positioning the latter. A flexible covering strip, preferably transparent, is arranged to cover the bent tongues referred to, after the stencil-sheet has been attached to the carrier-sheet thereby. A flexible strip of fabric or other suitable material is secured to the upper or leading edge of the carrier-sheet, to form a continuation thereof, to facilitate the drawing through the typewriter feed-rolls of the following portions of the carrier and stencil-sheets with the interposed absorbent backing-sheet. Other details of the construction will appear more fully hereinafter.

In order that my invention may be more clearly understood, attention is hereby directed to the accompanying drawings form-

ing part of this application and illustrating one embodiment of my invention. In the drawings Figure 1 represents a plan view of a carrier-sheet having a backing-sheet and 5 stencil-sheet positioned thereon, certain parts being shown broken away; and Fig. 2 is an enlarged partial section of the same taken on line 2-2 of Fig. 1.

In the drawings the carrier-sheet proper, 10 represented at 1, is formed of a flexible material, which is hard and non-absorbent of the moistening fluid used for the stencil. As stated, this material is preferably celluloid, which may be obtained in sheets 15 of uniform thickness, and of a sufficient flexibility to enable the same readily to be positioned in a typewriter. Preferably, if the sheet is of celluloid, its rear surface may be roughened as by sand-blasting, or provided 20 with some friction means to prevent the slipping of the same in the typewriting machine. I have illustrated a pair of thin strips 2, 2, of rubber or the like, secured on the rear surface of sheet 1 for this purpose. 25 The celluloid carrier-sheet 1 preferably has a flexible strip 3 secured to the upper edge thereof to form an upward extension thereof. This strip 3, which I may term a leader, is adapted to facilitate the drawing 30 through the feed-rolls of a typewriting machine of the more bulky portions of the carrier-sheet and parts carried thereby. It is preferably somewhat thinner than the carrier-sheet 1 proper, and is formed of any 35 suitable material such as rubberized cloth. It may be secured to the carrier-sheet 1 by lines of stitching 4.

The carrier-sheet is provided adjacent its upper edge with suitable means for detachably securing the stencil-sheet thereto. Such securing means preferably take the form of a row of tongues 5 which are formed integral with the upper edge of the celluloid-sheet 1, these tongues extending forwardly 45 through openings in the leader 3 and being bent upwardly on the front side of the same.

The stencil-sheet 6 is preferably of the type disclosed in Patent No. 1101258 referred to, and may consist of a dry but hygroscopic sheet of fibrous material impregnated with coagulated protein. My invention is not limited to the use of a stencil-sheet of this character, however, since various advantages may be obtained from the invention when other types of stencil-sheet are used.

In the embodiment of my invention illustrated, the stencil-sheet is secured at its upper edge to a strip 7 of varnished paper which is provided with a horizontal series of openings 8 through which the tongues or projections 5 on the carrier-sheet are adapted to be inserted. The stencil-sheet 6 may be 65 secured to said strip along its upper edge by

adhesive material or otherwise. The openings 8 in the stub 7 are preferably slots of a keyhole shape, so that the stencil-sheet when cut may be fastened in position on the drum of a rotary duplicating machine in the usual way.

A guard or abutment strip 9 is preferably secured in horizontal position upon the face of the leader 3 immediately above the upwardly extending tongues 5. When the 75 stencil-sheet is positioned on the carrier-sheet by slipping the tongues 5 through the slots 8, the upper edge of the stub 7 of the stencil-sheet will register with the lower edge of the strip 9, so as to properly align 80 the stencil-sheet on the carrier-sheet. The abutment 9 need, of course, not be a continuous strip.

The front face of the carrier-sheet 1 is preferably provided with limitation lines 10 85 adjacent its top, bottom and side edges with index figures 11, or other suitable indicia printed adjacent to the lines 10. These indicating lines and figures are for the purpose of aiding in the spacing of the stencil 90 work done and to keep such work within the limits of the printing capacity of the duplicating machines employed. These indicia should be visible to the operator during the act of making a stencil, either by showing 95 through the stencil or by appearing beyond certain edges of the stencil-sheet.

A flexible covering strip 12 is secured to the front face of the leader 3 so as to normally lie over the tongue or slot securing 10 devices for the stencil sheet, as well as the abutment strip 9. The covering strip 12 is preferably transparent and may conveniently be formed of celluloid. It is secured along its upper edge to the leader 3 as by 10 horizontal rows of stitching 13. In its normal position it lies flat over the stub 7 of the stencil-sheet together with the tongues 5 and the abutment strip 9, so as to protect these parts while the device is being drawn 11 through a typewriting machine. The protective strip 12 may be raised when the stencil-sheet is to be secured in position or detached. When it is in its covering position it aids in holding the stencil-sheet in 11 position, the tongues and slots, abutment strip 9, and to some extent the protective strip 12, all co-operating to prevent shifting of position of the stencil-sheet after it is attached to the carrier-sheet, the stencil-sheet 1: thus being attached to the carrier-sheet in a fixed position relative to the limiting indicia of the carrier-sheet.

When the device is to be used the stencil-sheet is attached to the carrier-sheet, and if the stencil-sheet is of the character which requires moistening before using, the stencil-sheet is lifted or thrown back and the backing-sheet 14 placed upon the carrier-sheet 1. This backing-sheet is of absorbent ma- 1

terial such as cloth, paper or other fabric. It is laid smoothly on the carrier-sheet and is moistened in the usual manner with the desired moistening fluid, after which the 5 stencil may be swung back into position to lie upon the same and to receive moisture therefrom. The carrier-sheet 1 is entirely non-absorbent, so that all of the fluid will be effective for moistening the stenciling 10 sheet. When the stencil has been cut, it may be unfastened from the carrier-sheet and positioned in a duplicating machine whenever desired.

By the use of a material such as celluloid, 15 which is naturally non-absorbent, for the carrier-sheet, a higher degree of protection against damage of the same by moisture is obtained than when a varnished paper carrier-sheet is used, while at the same time the 20 cost of individual carrier-sheets as previously used is eliminated. The stubs 7 may be scored so as to cause the same to conform to the contour of the cylinder of the duplicating machine, thereby eliminating the 25 present method of bending them by hand.

As previously stated, the use of the hard backing surface provided by the carrier-sheet of celluloid or the like, results in a characteristically fine lined stencil. Accordingly, 30 the deposit of ink formed on duplicates will be lighter than in the previous practice, because of which the deposit will be more readily absorbed. The necessity which now frequently arises to speed the 35 impression sheets through a duplicating machine by an abnormally rapid turning of the cylinder, in order to prevent a heavy, mussy deposit of ink, will be entirely eliminated. The blotchy effects in portions of 40 duplicating work sometimes seen, resulting from the accidental spreading of moisture to the back surface of the carrier-sheet, will be entirely eliminated. There will be less halo about the letters where lightweight papers 45 are used, and less offset.

It should also be noted that the hard carrier-sheet affords sufficient resistance to the impact of the type of a typewriting machine applied through the stencil-sheet, to 50 make a good result no matter what the character of the interposed absorbent backing-sheet may be. It is, therefore, possible to use as the backing-sheet a sheet of cloth mesh, similar to the material of which a 55 typewriter ribbon is composed, for the purpose of obtaining results which quite closely resemble the prints made by a typewriting machine through an ink ribbon. The hardness of the carrier-sheet also makes easier 60 the work of the typewriter operator in making the stencil, in that capital letters and special characters will not have to be struck twice, and no care will have to be taken to minimize heavy letter effects as in the case 65 of such type characters as "l," "r," "t."

Similarly, troubles resulting from the use of a too soft platen on the typewriter are eliminated. Where stencil-sheets have become tough through deterioration, the necessary resistance for the type impact will be 70 available.

It will be understood that my invention is not limited to the exact details of construction described, but that the same is of a broad and comprehensive character, within 75 the scope of the appended claims.

What I claim is:-

1. In stenciling material, the combination of a hard flexible entirely non-absorbent carrier-sheet, a stencil-sheet of dry but hygroscopic character, and an absorbent backing-sheet adapted to be inserted between said stencil and carrier sheets, said stencil and carrier sheets being adapted and arranged for ready and repeated attachment to and 85 detachment from each other. 80

2. In stenciling material, the combination of a celluloid carrier-sheet and a stencil-sheet, said sheets being adapted and arranged for ready and repeated detachment 90 from and attachment to each other, with the stencil-sheet superposed above the carrier-sheet.

3. In stenciling material, the combination of a flexible non-absorbent carrier-sheet, of 95 a hardness considerably greater than that of cardboard or paper, varnished or unvarnished, and a stencil-sheet of dry but hygroscopic character, said sheets being arranged for ready attachment to, and detachment 100 from, each other.

4. In stenciling material, the combination of a celluloid carrier-sheet, a stencil-sheet of dry but hygroscopic character, said sheets being adapted and arranged for ready attachment to and detachment from each other, and a separate absorbent backing-sheet, adapted to be inserted between said carrier and stencil sheets. 105

5. In stenciling material, a celluloid carrier-sheet having means thereon for the ready and positive attachment thereto of a stencil-sheet. 110

6. In stenciling material, a flexible carrier-sheet adapted for use with successive 115 stencil-sheets, having means thereon for the ready attachment thereto of successive stencil-sheets, and guard means adapted to prevent shifting of position of a stencil-sheet on said carrier-sheet, after attachment thereto. 120

7. In stenciling material, a flexible carrier-sheet adapted for use with successive stencil-sheets, and having mechanical means thereon for the ready and successive positive attachment thereto or detachment 125 therefrom of stencil-sheets.

8. In stenciling material, a flexible carrier-sheet adapted for use with successive stencil-sheets, having means thereon for the ready attachment thereto of edge portions 130

- of successive stencil-sheets, and a flexible strip attached to said carrier-sheet, in position to extend over, and be moved away from, said attachment means.
- 5 9. In stenciling material, a carrier-sheet of flexible non-absorbent material having a hardness considerably greater than that of varnished cardboard or paper, adapted for use with successive stencil-sheets, and
- 10 having projections bent upwardly from the upper surface thereof for coöperation with a stencil-sheet in attaching the latter thereto, and a flexible strip attached on one edge thereof to said carrier-sheet to normally
- 15 cover said projections.
10. In stenciling material, a celluloid carrier-sheet, having means on the rear surface thereof to prevent slipping thereof on a surface on which the same may be placed while
- 20 a stencil is being made.
11. In stenciling material, a celluloid carrier-sheet, adapted to have a stencil-sheet secured thereon, and a flexible strip secured to the upper edge thereof and forming an
- 25 upwardly extending continuation thereof, and adapted to facilitate the drawing of said carrier-sheet and a stencil-sheet carried thereby, through the feed-rolls of a type-writing machine.
- 30 12. In stenciling material, a celluloid carrier-sheet, adapted to have a stencil-sheet secured thereon, and a flexible leader strip of thinner material than said carrier-strip, secured to the upper edge and forming an
- 35 upwardly-extending continuation of said carrier-strip.
13. In stenciling material, a carrier-sheet of flexible material having projections adjacent its upper edge for coöperation with
- 40 a stencil-sheet in attaching the latter thereto, a flexible leader strip secured to the upper edge of said carrier-sheet to form a continuation thereof, and a flexible strip attached at one edge thereof to said leader
- 45 strip in position to normally cover said projections.
14. In stenciling material, a carrier-sheet of flexible material having projections adjacent its upper edge for coöperation with a
- 50 stencil-sheet in attaching the latter thereto, an abutment strip on said carrier-sheet adjacent said projections, against which the edge of a stencil-sheet may abut, and a transparent flexible strip attached at one edge to
- 55 said carrier-sheet in position to normally ex-
- tend over said projections and abutment strip.
15. In stenciling material, the combination of a celluloid carrier-sheet, a stencil-sheet of dry but hygroscopic character super- 60 posed thereon, and a flexible leader strip secured to the edge of said carrier-sheet which is first to be inserted in a typewriting machine.
16. In stenciling material, the combination 65 of a carrier-sheet, flexible and non-absorbent and of a hardness considerably greater than that of varnished cardboard or paper, and a stencil-sheet of dry but hygroscopic character having an attachment strip 70 at one edge thereof, said attachment strip and carrier-sheet having coöperating attachment devices.
17. In stenciling material, the combination 75 of a carrier-sheet, flexible and non-absorbent and of a hardness considerably greater than that of varnished cardboard or paper, and a stencil-sheet having an attachment strip at one edge thereof, said attachment strip and carrier-sheet having key-hole openings and upwardly extending bent
- 80 projections, adapted to be inserted through said openings, respectively.
18. In stenciling material, the combination 85 of a flexible carrier-strip, a row of upwardly-extending projections thereon, and an abutment strip thereon, and a stencil-sheet having openings through which said
- 90 projections may extend and an edge adapted to abut against said strip.
19. In stenciling material, the combination 95 of a flexible carrier-strip, having a row of upwardly-extending projections thereon, a stencil-sheet having openings through which said projections may extend, and a flexible protective strip secured at one edge to said carrier-sheet and adapted normally to lie over said projections.
20. In stenciling material, a celluloid carrier-sheet having means thereon for the 100 ready attachment thereto of a stencil sheet, and a stencil sheet adapted to be used with said carrier sheet.
- This specification signed and witnessed this 20th day of February, 1920.
